(57) **CLAIM**

The ornamental design for a paper fastener prong cover invention, as shown and described.

DESCRIPTION

FIG. 1 is a top perspective view of a preferred embodiment shown in a closed orientation.

FIG. 2 is a top perspective view of a preferred embodiment shown in an open orientation.

FIG. 3 is a top view of the preferred embodiment shown in an open orientation.

FIG. 4 is a bottom view of the preferred embodiment shown in an open orientation.

FIG. 5 is a right side view of the preferred embodiment where the left view is a mirror image of this figure shown in an open orientation.

FIG. 6 is a front view of a preferred embodiment shown in an open orientation.

FIG. 7 is a back view of a preferred embodiment shown in an open orientation.

FIG. 8 is a top view of the preferred embodiment shown in a closed orientation.

FIG. 9 is a bottom view of the preferred embodiment shown in a closed orientation.

FIG. 10 is a right side view of the preferred embodiment where the left view is a mirror image of this figure shown in a closed orientation.

FIG. 11 is a front view of a preferred embodiment shown in a closed orientation; and,

FIG. 12 is a back view of a preferred embodiment shown in a closed orientation.

The King Fastener trademark forming part of the claimed design is a trademark of Manuel Ang that has not yet been registered.

The broken lines in FIGS. 1 and 2 represent paper and the paper fastener prongs and are not part of the claimed design and are being shown for the convenience of illustration.
